UNITED STATES PATENT OFFICE.

JOSEPH M. FRAAZ, OF NEW YORK, N. Y.

LINE-ADJUSTER FOR TYPE-WRITER PLATENS.

1,136,223.

Specification of Letters Patent.

Patented Apr. 20, 1915.

Application filed February 18, 1914. Serial No. 819,373.

To all whom it may concern:

Be it known that I, JOSEPH M. FRAAZ, a citizen of the United States, and a resident of the city of New York, borough of Manhattan, in the county and State of New York, have invented a new and Improved Line-Adjuster for Typewriter-Platens, of which the following is a full, clear, and exact description.

10 This invention relates to typewriting, adding or analogous machines including a circumferentially movable or adjustable roller or platen.

15 Among the objects of the invention is to provide an attachment adapted to be added to any usual or conventional form of typewriting machine to which the attachment is applicable for the purpose of adjusting the platen or roller to any desired extent less 20 than the full space adjustment.

25 More specifically stated, I provide an attachment for the end of the platen shaft providing, in connection with the usual ratchet wheel, a special finger wheel having connection with the shaft independent of the usual finger wheel whereby the platen may be rotated to any extent independently 30 of the usual means for rotating it and without interfering in any manner with the usual step-by-step line adjustment.

35 The foregoing and other objects of the invention will hereinafter be more fully described and claimed and illustrated in the drawings forming a part of this specification in which like characters of reference indicate corresponding parts in all the views, and in which—

40 Figure 1 is an elevation of one end of a platen showing my invention applied thereto, parts being in elevation and other parts in section; Fig. 2 is a similar view but with the new attachment substantially in central longitudinal section; and Figs. 3, 4 and 5 are vertical transverse sections on the corresponding lines of Fig. 1.

45 The several parts of the device may be made of any suitable materials, and the relative sizes and proportions, as well as the general design of the mechanism, may be varied to a considerable extent without departing from the spirit of the invention hereinafter more fully set forth and specifically claimed.

50 Referring to the drawings for a more 55 specific description of the invention I show at 10 a typewriter platen having secured

thereto a shaft 11 journaled in a bearing 12 of the frame 13.

A ratchet or master wheel 14 is or may be substantially similar to the corresponding wheels now generally employed in typewriting, adding or analogous machines for the purpose of rotating the platen step by step and holding the same steady while the writing is being performed. This wheel 14, however, is journaled loosely upon the shaft 11 and is secured to a special form of finger wheel casing 15 which, through certain peculiar connecting means, serves to rotate the platen in either direction in a manner corresponding to the usual practice.

Within the casing 15 is a floating or rotatable frame or spider 16 having a hub secured as by means of a set screw 17 to the end of the shaft 11. Said spider serves to support in various bearings a plurality of gear devices having interlocking and operating connection with the aforesaid ratchet wheel 14 whereby the function of rotating the platen directly by hand through the casing 15 may be accomplished. At 17 I show a worm journaled in bearings 18 in said spider, and said worm is in constant mesh with a worm wheel 19 secured to the ratchet wheel 14. A positive rotation of the casing 15 through the ratchet wheel and worm wheel connections with the spider will cause a corresponding rotation of the platen due to the well known interlocking feature between a single pitch worm and its worm wheel.

For the purpose of delicate adjustment of the platen so as to bring the paper into finer line adjustments than can readily be obtained by rotating the ratchet wheel, I provide means whereby the spider may be rotated independently of the ratchet wheel and its finger casing 15, and since the usual retaining means for the ratchet wheel remains functional to hold the ratchet wheel and the worm wheel stationary, the spider may be caused to creep or rotate slowly around the axis of the ratchet wheel and cause through the set screw 17 a corresponding slow rotation of the platen so as to effect the desired delicate adjustment of the paper. As a suitable and effective means for rotating the spider independently of the finger wheel 15, I provide an auxiliary finger wheel or knob 20 in axial alignment with the other finger wheel and secured to a short shaft 21 beyond the end of

and in axial alinement with the shaft 11. The short shaft 21 is journaled in the outer end of the casing 15 and carries on its inner end a gear wheel 22 meshing with a pinion 23 secured to a countershaft 24 journaled in the outer head 16' of the spider. Said countershaft 24 and its pinion 23, therefore, float with the spider around the axis of the shaft 11 during the rotation of the knob 20.

10 At 25 I show a shaft journaled in bearings 26 on the opposite or inner side of the head 16" of the spider from the worm 17. Said worm and shaft 25 carry pinions 28 meshing with each other whereby the worm 15 may be driven from the shaft 25 and by means of bevel gears 29 from the countershaft 24. Two heads 16' and 16" of the spider are maintained in proper spaced relation by means of stay rods 30.

20 The arrangement of gearing between the knob 20 and the worm wheel is such that a rotation of the knob 20 independently of the ratchet wheel 14 will cause a rotation of the platen in precisely the same direction as if the main finger wheel 15 were operated but at a slower speed.

The invention herein disclosed is of a simple, compact and comparatively cheap nature and may readily be applied but 30 with slight modification to any known form of typewriting machine or other machine having an adjustable roller. The gearing between the auxiliary knob 20 and the ratchet wheel 14 provides, as will be noted 35 from the description above, a very delicate line adjustment, and it is obvious that by suitably graduating the parts 15 and 20, as shown at 15^a and 20^a, respectively, Fig. 1, the operator may have definite and positive 40 control of the adjustment. The graduations may be variously arranged on these main and auxiliary wheels in accordance with the character of the gearing, so as to effect various possibilities of control.

45 Having thus described my invention, I claim as new and desire to secure by Letters Patent:—

1. The combination with a platen and its shaft journaled in a stationary bar, of a 50 ratchet wheel journaled on the platen shaft, a finger wheel casing connected to the ratchet wheel for simultaneous rotation therewith, an auxiliary finger wheel journaled in the outer end of the casing and rotatable otherwise independently thereof, and reduction gearing connections between said auxiliary finger wheel and the shaft whereby the shaft and platen may be rotated while the ratchet wheel and the casing remain stationary.

60 2. The combination with a roller and its shaft journaled in a fixed bearing, of a master wheel including a casing, a gear wheel within the casing secured to the master wheel, a floating spider within the cas-

ing secured to the shaft, a set of gearing carried by said floating spider and meshing with said first mentioned gear wheel, and a knob rotatable independently of the casing and master wheel to operate the set of gearing and thereby rotate the roller at a slow speed while the master wheel remains stationary.

3. In a device of the character set forth, the combination of a shaft, a master wheel journaled on the shaft, a worm wheel secured to the master wheel, means to rotate the master wheel, and gear connections including a worm meshing with the worm wheel to cause positive rotation of the shaft 75 during rotation of the master wheel.

4. The combination of a shaft, a master wheel journaled thereon, a worm wheel secured to the master wheel, a spider secured to the shaft adjacent the worm wheel, a 85 countershaft journaled in the spider parallel to the first mentioned shaft, means to rotate the countershaft independently of the master wheel, and gear connections between the countershaft and the worm wheel, said connections including a worm meshing with the said worm wheel whereby a rotation of the master wheel will cause similar rotation of the shaft or a rotation of the countershaft will cause a slow rotation of the main 95 shaft while the master wheel remains stationary.

5. In a typewriting or adding machine, the combination with a line space wheel journaled loosely on a shaft, a worm wheel 100 secured to said line space wheel, a worm meshing with the worm wheel, a countershaft, a train of gears, and an auxiliary finger wheel meshing with said gears for turning the platen in the same direction as 105 said auxiliary finger wheel is turned.

6. In a typewriter or adding machine, the combination with a shaft and a line space wheel loosely mounted thereon, of a casing 110 secured to the line space wheel and rotatable step by step therewith, a direct finger wheel associated with said casing for rotating it and the shaft, a floating member adapted to float within the casing and secured to the shaft, an auxiliary finger wheel 115 adjacent the end of the casing and coaxial therewith, and connections between the auxiliary wheel and the floating member serving to cause rotation of the floating member and shaft in the same direction as 120 the auxiliary wheel but at a different angular velocity.

7. In a typewriter or adding machine, the combination of a shaft, a line space wheel 125 journaled loosely thereon, a worm wheel secured to said line space wheel, a worm meshing with said worm wheel, a floating spider secured to the shaft, a countershaft, a train of gears between the countershaft and the worm, an auxiliary finger wheel, and reduc- 130

tion gear connections between the auxiliary finger wheel and the countershaft, substantially as and for the purposes set forth.

8. In a typewriting or analogous machine, a rotary shaft, a platen secured thereto, a casing and a coaxial worm wheel connected with each other, both casing and worm wheel being journaled loosely on said rotary shaft, a main finger wheel combined with the casing for direct rotation of the shaft, a gear housing floating within the casing and secured to the shaft, a worm carried by said housing and meshing with a

worm wheel, an auxiliary finger wheel adjacent the main finger wheel, and reduction gearing between the worm and the auxiliary finger wheel for rotating the shaft at a predetermined slower speed.

In testimony whereof I have signed my name to this specification in the presence of two subscribing witnesses.
